CONCEALED FLAP FASTENER

Robert M. Kerr, Louisville, Ky.

Application March 22, 1938, Serial No. 197,444

1 Claim. (Cl. 229—84)

My invention relates to improvements in flap fasteners, particularly useful in fastening unsealed envelopes and it is primarily intended to take the place of metal clasps, string and button ties and other types of fasteners, now extensively used on open end envelopes.

Through the use of my fasteners, the passage of envelopes equipped therewith, through the mails will be facilitated, because of the concealed fastener which permits the flap to lie securely fastened against the wall of the envelope, without projections of any kind to catch against other packages in the mail.

While my concealed flap fastener is particularly useful in fastening the flaps of unsealed open end envelopes, it can be used advantageously on other types of envelopes, also on folders and on any other article which employs a flap folded over the open side of the article.

Furthermore, envelopes equipped with my fasteners will present a neat, clean cut appearance, and they can be manufactured at a substantial saving in cost as compared with those equipped with metal fasteners, string and button and other types of flap fasteners, now generally used.

The device by which, and the manner in which, I attain these ends is presently to be described.

In the drawing,

Figure 1 represents an ordinary open end envelope with flap open and extended, and showing the tongue or fastener affixed thereto by means of a further extended portion of the flap being bent back and affixed by adhesive to the inner wall of the flap in such manner as to reinforce the flap and also to provide a fastening for the free and extended portion comprising the tongue or fastener. By this arrangement, the entire envelope, the flap and the tongue or fastener are of one piece construction.

Figure 2 represents the same type of open end envelope with the flap open and extended, but having a portion of the tongue or fastener affixed to the inner wall of the flap by pasting adhesive and a free portion of the same comprising the extended tongue or fastener. This constitutes two piece construction and is simply another means for securing the tongue or fastener to the flap alternative to the means employed for the same purpose as shown in Figure 1.

Figure 3 represents a perspective view of a portion of the envelope of Fig. 1, showing the tongue or fastener bent down in such manner as to be easily inserted into the slot shown below in the wall of the envelope.

Figure 4 represents a portion of an envelope

of either form, shown with the flap closed as it would appear to the eye when the envelope is closed and the tongue or fastener is inserted into the slot, part of the tongue or fastener being concealed beneath the closed flap and the remaining portion of the tongue or fastener being concealed in the inside of the envelope, after it has been passed through the slot, which slot is placed in position directly underneath the closed flap by which it is completely concealed.

Like letters and figures of reference indicate different parts and features of the drawing.

In the drawing, reference is now to be had to Figure 1 in which the letter A represents the outer wall of an ordinary open end envelope. The letters B—B show portions of the flap of the envelope integral with the portion C and the portion D. C being the inner wall of the flap and D being the free portion. The portions B—B have been bent back and affixed by adhesives to the portion C leaving the portion D unaffixed by adhesives and free from the lines G at which point the tongue or fastener is indented or scored to facilitate bending of the same for easy insertion through the slot E into the body of the envelope A. The broken line F represents a ring of paper or other material affixed to the inner wall of the envelope to reinforce the slot.

Under this arrangement, the entire envelope, including the flap, the reinforcement of the same and the free portion constituting the tongue or fastener are all in one piece.

In Figure 2, the letter A represents the outer wall of an ordinary open end envelope. The letter B represents a separate portion of paper, card board, combined paper and fabric, multiple ply paper or any suitable material, the same being affixed by adhesive to the inner wall of the flap C with an extended portion D constituting the tongue or fastener free from the line of indentation or scoring G adapted to bend along the lines G for easy insertion through the slot E into the body of the envelope A. The broken lines F represent a ring of paper or other material affixed to the inner wall of the envelope to reinforce the slot.

Under this arrangement, the use and purpose of the tongue or fastener is identical with the arrangement shown in Figure 1 except that the tongue and fastener is separate and must be affixed to the flap by a proper adhesive, requiring two-piece construction.

Figures 3 and 4 have been described heretofore and are intended only as aids in visualizing the method of inserting the tongue or fastener into

the slot and the concealed state of the tongue or fastener after the flap is closed.

In closing the envelope, it is a very simple matter to direct the fastener through the slot and into the envelope, where it is firmly and securely established as a secure fastening for the flap of the envelope. The flap, so fastened, can be readily and easily opened for postal inspection and when so opened, it can be reclosed without mutilation of any part of the flap, envelope or fastener.

While the foregoing forms and materials mentioned in the description relating thereto, are the preferable forms of my invention, I do not desire to be confined to the several forms of the tongue or fastener, or to the type of envelope described, but to any other form or forms, in which and through which, the use of my concealed tongue and fastener and my concealed slot may be usefully employed within the spirit of my invention.

Having thus described my invention so that one

skilled in the art appertaining thereto may make and use it, I claim:

In a concealed flap fastener for an unsealed envelope or other like article having a flap folding over the opening thereto, a tongue or fastener, firmly affixed by adhesives or other suitable means to the inside surface of the said flap; said tongue or fastener being of single ply or multiple ply construction, comprising paper, card board or other suitable material; said tongue or fastener having a line of indentation or scoring transversely across its surface at a point of separation between an affixed portion and a free, ungummed and extended portion of the said tongue or fastener; said line of indentation or scoring being adjacent to, and parallel with the lower edge of the said flap; said line of indentation or scoring being designed to act as a hinge to facilitate easy and repeated bending of the said tongue or fastener, substantially as described.

ROBT. M. KERR.
